GARMENT HANGER

Arthur A. Pedersen, Orinda, Calif.

Application April 22, 1953, Serial No. 350,326

4 Claims. (Cl. 223—95)

1

The present invention relates to improvements in garment hangers and more particularly to improvements in that type of garment hanger designed to suspend trousers or skirts in upright position by engagement at the belt line.

The present invention provides a garment hanger which is simple in construction and which may be readily adjusted to accommodate trousers or skirts of various waist dimensions. Essentially, the device comprises a pair of relatively adjustable members one of which is provided with forking arms having ends adapted to engage within the belt line of a garment adjacent the upper end of the front trouser crease of a pair of trousers, and the other of which is provided with a garment engaging end adapted to engage within the belt line adjacent the rear seam. Means are provided for drawing the front central portion of the trousers inwardly between the forking arms comprising, in the embodiment disclosed, a garment engaging hook carried by one end of a tension spring, the opposite end of which is anchored to one of the relatively adjustable members. Means are provided for suspending the hanger from a support, preferably including a hook connected to a loop carried between the arms of the forked member, which loop encompasses the spring just described so as to hold it approximately in its operating position. The spring may be anchored to the forked member adjacent its base, but is preferably anchored to the member which is adjustable with respect to the forked member, since this arrangement provides for increasing the tension of the spring as the device is expanded to accommodate larger garments.

The novel structure of the invention is defined with particularity in the appended claims. The invention itself, however, together with additional objects and advantages thereof, will be best understood from the following description of specific embodiments thereof when read in connection with the accompanying drawing, in which:

Figure 1 is a plan view of a garment hanger embodying the present invention;

Figure 2 is a view in side elevation of said garment hanger, one of the arms being broken away to expose underlying parts;

Figure 3 is a detail view in section of a portion of the garment hanger of Figures 1 and 2; the section being taken on the line 3—3 of Figure 2;

Figure 4 is a detail view in section of a portion of the garment hanger of Figures 1 and 2, the section being taken on the line 4—4 of Figure 1;

2

Figure 5 is a detail view in section of a portion of the garment hanger of Figures 1 and 2, the section being taken on the line 5—5 of Figure 2;

Figure 6 is a perspective view of the garment hanger of Figures 1 and 2 illustrating the manner in which a pair of trousers are supported thereon;

Figure 7 is a detail view, in plan, of a portion of a modified embodiment of the invention; and

Figure 8 is a detail view, in side elevation, of a portion of the modified form of garment hanger illustrated in Figure 7.

As illustrated in Figures 1 to 6, inclusive, the garment hanger of the present invention comprises a pair of relatively adjustable members 10 and 20 which may conveniently be made either of metal or of molded plastic composition having sufficient flexibility and resiliency. The first member 10 is provided with forking arms 11 and 12 each provided with a garment engaging end illustrated as in the form of knobs 13 preferably provided with serrations 14 to minimize the tendency of a garment to slip out of engagement therewith. As shown, each of the arms 11 and 12 is provided with a reinforcing rib 15 and is of gradually increasing cross-sectional area as the juncture of the arms 11 and 12 is approached, so that the flexing of the arms 11 and 12 during use of the device is substantially confined to those portions of said arms between the points 15 and the ends 13.

Means are provided for adjustably connecting the second member 20 with the member 10. In the embodiment illustrated in Figures 1 to 6, inclusive, this means comprises a portion 16 of the member 10 extending from the juncture of the arms 11 and 12 in a direction opposite to the direction in which those arms extend and provided with a series of bayonet slots 17. The member

20 is formed as a channel section, as shown, the interior of which fits in slidably engagement over the portion 16 of the member 10 and the upper web 21 of which seats in an offset 18 of the member 16. The member 20 is also provided with

a cross-pin 22 adapted to enter any of the bayonet slots 17 of the portion 16 and to be resiliently latched therein by snapping under a lip 19 of any of the slots 17. The member 20 is also provided with a garment engaging end 23 provided with serrations 24 similar to the garment engaging ends 13 of the members 11 and 12.

Means are provided for drawing a portion of a garment inwardly between the forking arms 11 and 12 of the member 10. In the illustrated embodiment, this means comprises a garment engaging element in the form of a hook 30 which

may be formed of metal or plastic and ribbed as at 31 for reinforcement. A tension spring 32 is attached at one end, as at 33, to the hook 30 and at its other end, as at 34, to an anchor 35 carried by the member 10.

Means are also provided for suspending the hanger from a support. In the illustrated embodiment this means comprises a loop element 40 carried between the arms 11 and 12 of the member 10 between the points 15 thereof and the juncture of said arms, being preferably pivotally mounted between the arms 11 and 12 as by trunnions 41 which may be snapped into aligned journals in the arms 11 and 12 by a very slight flexing of the portions of the arms 11 and 12 between the points 15 thereof and the juncture of the arm. A conventional garment hook 42 is pivotally mounted in an aperture 43 in the upper portion of the loop 40. In the assembly of the device, the spring 32 is preferably passed through the loop 40 so that the latter confines the spring 32 to movement in a locus closely adjacent the position occupied by the spring when the device is in use, thus not only facilitating packaging of the device, but also making it unnecessary for the user to search and fumble for the hook 33 in using the device.

The modified embodiment of the invention illustrated in Figures 7 and 8 is identical in all respects to the embodiment illustrated in Figures 1 to 6, inclusive, except in the provisions for adjustably connecting the members 10 and 20 and anchoring the spring 32. In the modified form of the device, the extension 16 of the member 10 instead of being made in the form shown in Figures 1 to 6, inclusive, is made in the form of a U-shaped channel 16a, while the member 20, instead of being made in the form shown in Figures 1 to 6, is made in the form of a flat strip 20a and is provided with a series of holes 22a adapted to align with a single hole 16b in the portion 16a of the member 10. This arrangement is such that the member 20a may be slid in one direction or the other through the channeled portion 16a of the member 16 and anchored in any desired position by passing a bolt 50 through the aperture 16b and any desired one of the holes 22a and thereafter tightening the wing nut 51 on said bolt.

In this embodiment illustrated in Figures 7 and 8, the spring 32, instead of being anchored to a spring anchor integral with the member 10, as in the embodiment illustrated in Figures 1 to 6, inclusive, is anchored to an anchor 35a formed on the end of the member 20a. This arrangement is such that as the member 20a is moved leftward, as viewed in Figures 7 and 8, the spring anchor 35 is moved leftward a corresponding distance and greater tension is thus applied to the spring 32 for an advantageous purpose which will be evident in contemplating the operation of the device.

The operation of the device is clearly illustrated in Figure 6 of the accompanying drawing show-

ing the garment hanger of the present invention applied to a pair of trousers. As shown, the hanger of the present invention is inserted within the waist band of the trousers with the garment engaging end 13 of the arms 11 and 12 disposed adjacent the upper ends of the front creases of the trousers, while the garment engaging end 23 of the member 20 is disposed adjacent the rear seam of the trousers. The hook 30 is then grasped by the operator and, the trousers being completely closed at the front, this hook is engaged over the edge of the trousers in alignment with the front opening thereof and released so that the spring 32 may then draw that portion of the trousers in between the arms 11 and 12 to the position shown; the spring 32 being so proportioned in length and strength as to hold the trousers securely upon the garment hanger in this position, with the spring 32 under substantial tension. The trousers being thus secured on the hanger, they then may be readily suspended from any convenient support by the garment hook 42.

While the device of the present invention is particularly designed for use as a trouser hanger having advantages in such use in preserving the crease in the front of the trousers, it will be appreciated that it is also adapted to be employed as a skirt hanger as well as for other garments of a generally similar nature.

What is claimed is:

1. A garment hanger comprising a first member having forking arms each having a garment engaging end, a second member adjustably connected to said first member and having a garment engaging end, means for drawing a portion of a garment inwardly between said forking arms including a garment engaging element and a tension spring connected at one end to said element and at its other end to one of said members, and means for suspending said hanger from a support.

2. A garment hanger according to claim 1 in which the suspending means includes a loop element carried between said arms and enclosing said tension spring.

3. A garment hanger according to claim 1 in which said other end of said spring is connected to said first member.

4. A garment hanger according to claim 1 in which said other end of said spring is connected to said second member.

ARTHUR A. PEDERSEN.
